SHADE

Ward E. McKinney, Los Angeles, Calif.

Application November 19, 1938, Serial No. 241,367

6 Claims. (Cl. 156—17)

This application is a continuation-in-part of my copending application, Serial No. 219,630, filed July 16, 1938.

This invention relates to shades for windows and similar openings, comprising a plurality of slats adapted by their relative association and manipulation to vary the amount of light admitted through the opening.

An important disadvantage in many of the Venetian blinds of the prior art is that by reason of the necessary close relationship of the slats, they are difficult to clean, all slats comprising the blind being usually fastened together as an integral structure. Moreover, all slats are necessarily held parallel to one another, which prevents their being tilted except in unison and to the same angle.

It is a principal object of the present invention to provide a blind comprising a plurality of slats between a series of chains suspended from a top pivot bar, said slats being removable to facilitate cleaning.

Another object is to provide means for tilting groups of said slats to different angles with respect to each other and their horizontal position.

Another object is the provision of means to maintain imperforate slats of a blind with their ends in vertical alignment during all stages of their opening, closing and tilting movement.

Still another object is to provide auxiliary supporting means for the lower end of the blind to carry any predetermined number of slats in collapsed position thereon and thereby vary the length of the portion of the window covered by the blind.

Another object is to provide a slat-supporting bar substantially V-shaped in cross-section having its ends pivoted above its axis to a head plate or window lintel adapted to tilt on its points of pivot with the side edges of the top portion thereof maintaining their vertical alignment with the opposite side edges of the slats, respectively.

Other objects and corresponding advantages will be apparent to those of skill in the art from an examination of the following description read in the light of the accompanying drawing, in which:

Fig. 1 is a perspective view partially broken away with a tilting member in operative position between opposite slat-supporting chains to vary the angle of certain of the upper slats with respect to those below;

Fig. 2 is a perspective view of the blind held

in its uppermost collapsed position adjacent the top pivot bar;

Fig. 3 is a transverse sectional view of an upper portion of the blind in extended position illustrating the slat-tilting member in inoperative position;

Fig. 4 is a perspective view of a slat-retaining member adapted for attachment to individual slats to resist longitudinal displacement thereof;

Fig. 5 is an elevation of one of the tilting members for varying the angle of certain of the slats with respect to the others comprising the blind.

Referring to the drawing in detail, the numerals of which indicate similar parts throughout the several views, 6 designates a head plate 15 adapted for attachment to a window lintel or the like (not shown). Angle brackets 7 are secured above the window at opposite ends of head plate 6 in substantially horizontal alignment with each other. Each bracket 7 is formed with a laterally 20 extending arm 8 having a bearing 9 therein for a purpose about to be described. It will be understood that the brackets may be attached directly to the window lintel and thereby avoid the use of the head plate. A top bar 10 is provided, 25 which is triangular in cross-section, to form an upper flat surface 11 and sides 12 and 13 receding to a rounded corner 14. Axially aligned pins 15 are secured by any means well known in the art at each end of bar 10 intermediate the axis 30 of the bar and the top flat surface 11. Pins 15 are journaled in their respective bearings 9 to pivotally support bar 10. One of the brackets is formed with a slot 16 extending from the bearing 9 therein upwardly through the edge of the arm 8 through which a pin 15 may be moved to facilitate removal from and placement of the bar in its supporting brackets.

A pair of flexible slat-supporting ladders are suspended from bar 12 for supporting a plurality 40 of slats 17. Each ladder comprises a chain 18 secured at its middle to the top surface of the bar as at 19 with its ends extending over opposite side edges 20 and 21 of the bar and hanging vertically therefrom. The chain 18 of which the ladder is composed, preferred in the embodiment of the drawing, is of a type well known in the art and consists of a plurality of balls 22 connected and spaced apart by links 23. Below pivot bar 12 the opposite vertical reaches 24 and 25 50 of the chain are connected by a plurality of spaced transverse chains 26 which comprise the rungs of the ladder. The points on each vertical reach to which opposite ends of the respective transverse chains are connected are equi-spaced 55

from the respective edges 20 and 21 of the top surface of the bar, whereby each transverse chain 26 will be normally parallel with the top 11 of the bar. The spacing of chains 26 will be preferably less than the distance between the vertical reaches 24 and 25 of the chains, i. e., the width of the top surface 11 of the bar, in order to insure the overlapping of the slats 17 when the same are tilted as will hereinafter appear. Each slat 10 17 is supported on the transverse chains 26, and may be removed by sliding the slat longitudinally from between the pairs of vertical reaches 24 and 25 of the respective chains 18. It being desirable to normally maintain the ends 15 27 of the slats in vertical alignment with each other and the respective ends 28 of the top pivot bar, I provide a series of retaining members 29 comprising a strip of metal cut on spaced parallel lines intermediate the sides of the strip to form a 20 tab 30 which is turned over to overlie the opposite end 31 of the strip. A series of sharpened lugs 32 are secured to or cut from opposite faces of the clip and extend inwardly. The end of the strip from which the tab 30 is cut comprises a 25 pair of fingers 33 forming a slot 34 therebetween. One or more retaining members are employed with each slat 17 by clamping the tab and end 31 of the member on the edge portion of the slat 17 overlying the transverse chain 26 by which 30 the slats are supported, at the joinder of chain 26 with vertical reach 24 of the chains 18, and with the fingers 33 of the member engaging opposite sides of the adjacent portion of the vertical reach 24 of chains 18 to prevent longitudinal 35 movement of the slat with respect to the chain ladder.

It will be observed that the portion of the chains engaged by the respective fingers 33 may be manually withdrawn from between the fingers, 40 and the slats 17 thereby removed to facilitate cleaning without disengaging the members 29 from the slats.

Adjacent one or both ends of the shade, a chain 35 is provided for the tilting adjustment and 45 auxiliary support of the slats. Chain 35 is attached intermediate its ends and slightly at one side of its middle to the top surface of pivot bar 10 as at 36. The opposite reaches 37 and 38 of different length hang vertically from the edges 50 20 and 21 of bar 10 to a point slightly above the lower end of the shade when the latter is fully extended. The operator of the shade may, by pulling one of the vertical reaches 37 or 38 of the adjusting chain 35, partially rotate bar 10 on pins 15 and thus raise and lower the respective vertical reaches 24 and 25 of each chain 55 18 which will simultaneously tilt the transverse chains 26 to the same angle as the top surface 11 of the bar 10, thereby tilting slats 17 and varying the distance between the slats to restrict 60 the amount of light passing through the shade. The shade is raised manually by elevating the lowest slat 39 so as to collapse the slats successively from the bottom of the shade upwardly and support the collapsed slats on the manually elevated lower slat 39. The shade may be held 65 in any degree of collapsed or raised position by passing the longer reach 38 of chain 35 under the lower slat 39 and engaging a hook 40 of which several are secured along the length of the longer reach 38 of the adjusting chain 35 into one of a 70 series of eyes 41 carried in spaced relation by the shorter reach 37 of the adjusting chain. The hooks 40 are secured to the reach 38 of the adjusting chain a greater distance from the bar

than are the eyes 41 with which respective hooks 40 are adapted to engage to permit each hook to engage its complementary eye 41 at the side of the shade seen from the interior of the room.

The supporting structure for the slats 17 above described will normally hold each slat parallel to the top surface 11 of the pivot bar 10. If the user desired to tilt certain of the lower slats to a lesser angle than those slats of the upper part 10 of the shade, I provide a pair of tilting bars 42 having their opposite ends bifurcated to form slots 43 therein. Each bar is inserted between the groups of slats which are to be tilted to different angles with the bifurcations 44 of each end 15 of the bar engaging between the balls 22 of the opposite reaches 25 and 24 of each chain 18 adjacent the lower slat of the upper group and the upper slat of the lower group, respectively, if the slats are to be tilted so as to direct light upwardly into the room. Should it be desired to tilt the slats in the opposite direction the bars will engage the reaches 24 of each chain 18 adjacent the lower slat of the upper group between which the bars are inserted and correspondingly the 25 opposite ends of the bars will engage the reach 25 of the chain adjacent the upper slat of those slats below the bars. This position of the tilting bars 42 will affect the maximum variation in the relative degree of tilting of the slats of the two 30 groups. It will be observed that with the top surface of pivot bar 10 horizontally disposed as shown in Fig. 3, all slats of the blind will be in a horizontal position, and the bars 42 will be inoperative. Accordingly, the extent to which the top bar is tilted will determine the difference in the angle of tilting between the groups of slats above and below the tilting bars 42. While I have shown the ends of the tilting bars 42 engaging the opposite reaches of the chain adjacent 40 the slats, it will be understood that the bifurcations 44 of each end of the bars may engage between any of the balls of the portion of the chain 18 extending between the two groups of slats, which will result in a corresponding change in 45 the difference of the angle to which the slats of the two groups above and below the bars are tilted. Shorter bars (not shown) may be employed for this purpose, i. e., bars of a length equal to the distance between the points on the 50 chains at which the ends of bars are to engage. The bifurcations at one end of each bar may be clamped around the link with which they engage to prevent their loss when the bars are not used, i. e., when it is desired to tilt all slats to the 55 same angle.

While I have shown but one embodiment of my invention, it will be understood that numerous changes in size, shape, design, and proportion of the various parts may be made; that retaining 60 members 29 may be provided at each side of each slat to engage opposite reaches of each chain 18; that the hooks 40 and eyes 41 may be carried by reaches 37 and 38, respectively, of chain 35, if desired; that said chain 35 may be secured at its 65 middle whereby reaches 37 and 38 thereof will be of equal length, and the attachment of the hooks and eyes may be spaced along the chain equidistant from the top bar whereby they will engage one another under the lower slats; and that 70 the supporting chains, the transverse connecting chains, and the adjusting chain, or any of them, may be substituted by cords or tape, if desired, all without departing from the spirit of my invention as defined by the appended claims.

What I claim and desire to secure by Letters Patent is:

1. In a device of the character described, a pivot bar, a pair of vertical chains secured to the pivot bar to hang from the sides of said bar, a plurality of transverse chains, each secured to said vertical chains respectively, at points thereon equi-distant from said pivot bar and spaced apart with respect to each other, a slat slidably supported on each transverse chain, and a tilting bar between a pair of said slats having one end thereof engaging one of said vertical chains adjacent the next above slat and the other end of said bar engaging the other vertical chain adjacent the slat therebelow.

2. In a device of the character described, a pivot bar, vertical lines secured to said bar and hanging from opposite sides thereof, transverse lines secured to each of said vertical lines in spaced parallel relation, a slat carried by each of said transverse lines, a pair of adjusting lines attached to said pivot bar hanging from opposite sides of said bar, means of attachment secured to each of said adjusting lines intermediate the ends of said last-named lines to engage each other under said lowest slat.

3. In a device of the character described, a pivot bar, a pair of vertical lines secured to the pivot bar to hang from the sides of said bar, a plurality of transverse lines, each secured to said vertical lines, respectively, at points thereon equi-distant from said pivot bar, the points of attachment of said transverse lines, respectively, to said vertical lines, respectively, being spaced apart, a slat supported on each transverse line, and a member engaging the edge of each of said slats adjacent one of said vertical lines having a pair of fingers extending on opposite sides of said last-named vertical line to resist longitudinal movement of the slats to which the members are attached with respect to said vertical line.

4. In a device of the character described, a pair of brackets having an opening therein, means to support said brackets in spaced relationship, a pivot bar triangular in cross-section having a flat top and receding sides, pins attached at opposite ends of said bar intermediate the axis of the bar and the flat top thereof and parallel to the axis of the bar, chains hanging from each side edge of said bar, each chain comprising a plurality of balls connected by links, a plurality of transverse supporting lines, each connecting points on said chains equi-distant from said pivot bar, the points of attachment of each transverse line, respectively, being spaced from the points of attachment of the other of said transverse lines, a slat slidably supported on each of

said supporting lines, and means releasably engaging each of said slats and one of said chains to resist longitudinal movement of said slats with respect to said chains.

5. In a device of the character described, a pair of brackets having an opening therein, means to support said brackets in spaced relationship, a pivot bar triangular in cross-section having a flat top and receding sides, pins attached at opposite ends of said bar intermediate the axis of the bar and the flat top thereof and parallel to the axis of the bar, chains hanging from each side edge of said bar, each chain comprising a plurality of balls connected by links, a plurality of transverse supporting lines, each connecting points on said chains equi-distant from said pivot bar, the points of attachment of each transverse line, respectively, being spaced from the points of attachment of the other of said transverse lines, a slat slidably supported on each of said supporting lines, means releasably engaging each of said slats and one of said chains to resist longitudinal movement of said slats with respect to said chains, adjusting lines connected to said pivot bar and hanging therefrom on opposite sides of said slats, and means secured to each of said adjusting lines at different distances from said pivot bar with respect to each other and less than the length of said chains for attachment to one another under said lowest slat.

6. In a device of the character described, a pair of brackets having an opening therein, means to support said brackets in spaced relationship, a pivot bar triangular in cross-section having a flat top and receding sides, pins attached at opposite ends of said bar intermediate the axis of the bar and the flat top thereof and parallel to the axis of the bar, chains hanging from each side edge of said bar, each chain comprising a plurality of balls connected by links, a plurality of transverse supporting lines, each connecting points on said chains equi-distant from said pivot bar, the points of attachment of each transverse line, respectively, being spaced from the points of attachment of the other of said transverse lines, a slat slidably supported on each of said supporting lines, means releasably engaging each of said slats and one of said chains to resist longitudinal movement of said slats with respect to said chains, and means to tilt one of said slats to a different angle with respect to the top surface of the pivot bar comprising a member having its opposite ends releasably engaged with the respective chains and forming an acute angle with said chains.

WARD E. MCKINNEY.
